UNITED STATES PATENT OFFICE.

CHARLES M. PORTER, OF NEW YORK, N. Y.

DESIGN FOR A PRINTED FABRIC.

SPECIFICATION forming part of Design No. 24,715, dated September 24, 1895.

Application filed August 28, 1895. Serial No. 560,608. Term of patent 3½ years.

To all whom it may concern:

Be it known that I, CHARLES M. PORTER, a citizen of the United States, residing in the city of New York, county and State of New York, have invented and produced a new and original Design for Printed Fabrics, of which the following is a specification, reference being had to the accompanying drawing, showing a portion or piece of my newly-designed fabric.

The leading feature of my design consists in the parallel contrasting stripes intersected by vine-like or branched figures and leaves.

A represents a piece of fabric having par-

allel contrasting stripes B B'. C represents 15 the vine-like or branched figures intersecting the stripes and contrasting therewith, and D are the leaves arranged in pairs between certain of the figures C, intersecting the stripes and contrasting therewith. 20

What I claim is—

The design for printed fabrics, as shown and described.

CHARLES M. PORTER.
